SEED SPROUTER ASSEMBLY

George M. Sawyer, 8801 Calico Ave.,
Garden Grove, Calif. 92641

Filed Nov. 1, 1974, Ser. No. 520,111

Term of patent 14 years

Int. Cl. D11—02

U.S. Cl. D35—3 A

FIG.1.

FIG.2.

FIG.3.

FIG. 4.

FIG. 5.

FIG. 6.

FIG.7

FIG. 1 is a side elevational view of a seed sprouter assembly showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a cross-sectional view taken along lines 6-6 of FIG. 1 thereof; and

FIG. 7 is a perspective view showing the front, top, and right side thereof.

I claim:

The ornamental design for a seed sprouter assembly, as shown.
